US00D888694S

(12) **United States Design Patent** (10) **Patent No.:** **US D888,694 S**
(45) **Date of Patent:** **** Jun. 30, 2020**

(54) **ANTENNA**

- (71) Applicant: **ANTENNAS DIRECT, INC.**,
Ellisville, MO (US)
- (72) Inventors: **Corey Feit**, St. Louis, MO (US); **John Edwin Ross, III**, Moab, UT (US);
Richard E. Schneider, Wildwood, MO (US)
- (73) Assignee: **Antennas Direct, Inc.**, Ellisville, MO (US)

(**) Term: **15 Years**

(21) Appl. No.: **29/630,281**

(22) Filed: **Dec. 20, 2017**

(57) **CLAIM**

The ornamental design for an antenna, as shown and described.

DESCRIPTION

FIG. 1 is a perspective view of an antenna, showing our new design;

FIG. 2 is a back perspective view of the antenna shown in FIG. 1;

FIG. 3 is a front view of the antenna shown in FIG. 1;

FIG. 4 is a back view of the antenna shown in FIG. 1;

FIG. 5 is a right side view of the antenna shown in FIG. 1;

FIG. 6 is a left side view of the antenna shown in FIG. 1;

FIG. 7 is a top view of the antenna shown in FIG. 1; and,

FIG. 8 is a bottom view of the antenna shown in FIG. 1.
